FUEL AND AIR DIFFUSER BURNER

Ralph C. Brierly, Narberth, Pa.

Application December 19, 1947, Serial No. 792,829

4 Claims. (Cl. 158—76)

(Granted under the act of March 3, 1883, as amended April 30, 1928; 370 O. G. 757)

1

This invention relates to improvements in diffusers, and more particularly pertains to devices adapted to guide air and combustibles in fuel burners.

This application is a continuation-in-part of application Serial No. 655,358, filed March 18, 1946, now abandoned.

Modern fuel burners comprise three principal elements, an air register, through which air from the fireroom, double front or other reservoir is passed to the furnace and controlled; an injector or atomizer from which fuel is emitted; and a diffuser, which controls the function of intermixing intimately air and fuel in juxtaposition to the fuel injector. The subject invention presents improvements in such diffusers, whereby a plurality of diverse substances can be passed through the diffuser simultaneously, and whereby similar substances either at the same or at different static pressures or velocities, temperatures, or states of aggregation can be employed.

Diffusers or impellers employed in conventional fuel burners are constructed generally in the form of bladed frusto-conical sections, having flower-petal-like blades that impart rotation to the entering air stream, thereby imparting rotation to the flame and expanding said flame in the general shape of an inverted cone having its apex at the atomizer orifice. Such rotation of air causes the cone to expand to a greater height and base diameter than that of the cone formed by the atomized particles alone. This is a limiting characteristic, since a flame that converges to a point or needle, rather than a flame of increased cross-section with increased flame height, is often desirable. Moreover, it is advantageous to provide means whereby the volume or velocity of air or fuel can be varied without changing the diffuser. That is, it is at times desirable to change the relative velocities of the air and fuel being introduced to the flame so that the shape of the flame can be altered to suit the requirements of particular combustion processes while using a single type of diffuser.

Although it is well known to use bladed frusto-conical sections as diffusers in the registers of fuel burners, it has been found that such diffusers do not accomplish the objects hereinabove set forth, or, if some of them accomplish some of these objects incidentally or inadvertently, they do so with much less efficiency than that required.

The primary object of this invention is to provide a diffuser for guiding air and combustibles in a fuel burner, said diffuser being adapted to reduce flame-cone expansion, augment flame in-

2

tensity, and increase the speed of flame propagation.

Another object is to provide a diffuser of simple and durable construction wherewith compressed air can be introduced into a fuel burner, and fuels introduced therein through component elements of said diffuser.

A further object is to provide a diffuser adapted to create a flame cone diminished in diameter with travel from the atomizer of the fuel burner.

Still another object is to provide a diffuser that is operable as a supplemental fuel injector, being adapted to introduce oil, coal, gas or mixtures of these aggregates between or around the annular bands of said diffuser, either through spokes that retain said bands in spaced relation or through annular jackets positioned behind said bands.

Another object is to provide a diffuser that can direct streams of air or fuel in such a manner as to vary flame configuration and to effect cylindrical, conical, inverted conical, spherical and similar flame shapes.

A further object is to provide a diffuser that permits the simultaneous passage of fuels, air, combustion accelerators, combustion dampeners and other substances through adjacent annuli of said diffuser.

Further objects and advantages of this invention, as well as its construction, arrangement and operation, will be apparent from the following description and claims in connection with the accompanying drawings, in which:

Fig. 1 is a fragmentary sectional elevation of a diffuser mounted on the head of a fuel burner, showing a preferred embodiment of the invention;

Fig. 2 is an end view of said diffuser;

Fig. 3 is a plan view of a modified form of diffuser; and

Fig. 4 is a fragmentary elevation of the diffuser shown in Fig. 3.

Similar numerals refer to similar parts throughout the several views.

The fuel burner is provided with an outer wall 13. Port 17 in said wall is provided to carry the diffuser hereinafter described.

Sleeve 19 is secured normal to radial collar spiders 21, extending therethrough, and said spiders 21 are fastened removably to outer wall 13 by means of a plurality of bolts 23 and nuts 25. Said sleeve 19 carries a bolt 27 positioned exterior the outer wall and adapted to secure the multi-annular sleeve hereinafter described.

A multi-annular sleeve 29 carried slidably in sleeve 19 includes an inner conduit 31, medial

conduit 33 and outer conduit 35, said conduits 31, 33 and 35 being disposed concentrically. Medial conduit 33 is provided with a flared mouth 41 having an upstanding lip 43, the opposite end 41 being closed upon inner conduit 31 exterior of wall 13. Fuel-supply conduit 47 communicates with conduit 33 proximate end 45. Outer conduit 35, which is carried slidably in sleeve 19, is provided with a flared mouth 49 having an upstanding lip 51. The opposite end 59 of conduit 35 is closed upon medial conduit 33 exterior of wall 13, and fuel supply conduit 61 communicates with conduit 35 proximate said end 59.

Conduits 31, 33 and 35, and their respective mouths, are secured in the desired spaced relation by means of a plurality of radially disposed support-bars or spreaders 63, said spreaders 63 being secured to the edges of said mouths and defining a shallow frusto-conical figure. Fuel is also supplied through conduit 65, disposed in conduit 31 and extending beyond the end 39 thereof, connected with fuel atomizer 67, which is seated within ring 69. Said ring 69 is carried by the spreaders 63, and in turn mounts outwardly flared annulus 71.

A plurality of annuli 73, 75, 77 and 79 of frusto-conical shape are mounted on said spreaders, and said upstanding lips, extending therebeyond to continue or to subdivide the passageways defined by conduits 31, 33 and 35. Said annuli converge at selected angles as they extend from said spreaders and lips, as shown in Fig. 1. Supplemental fins 81 are secured to selected lips, spreaders and annuli further to subdivide and compartmentalize said passageways, suitable openings (not shown) in said fins permitting travel of combustibles therethrough.

In operation, sleeve 29 is adjusted fore or aft to desired position, and secured in that position by means of bolt 27. A plurality of substances are then fed through conduits 65, 31, 33 and 35 to atomizer 67 and the deflecting annuli, such substances being selected from the group including combustion constituents, generally being fuels, accelerators, catalysts, dampeners and the like, and including specifically, but not limited to, oil, gas, coal, compressed air, liquid air, steam, hydrogen peroxide, nitrogen dioxide, and manganese dioxide, or suitable combinations thereof. Such constituents are introduced at selected static pressures or velocities, temperatures, and in selected states of aggregation. For example, hydrogen peroxide can be pumped through one conduit and passageway, a solution of potassium permanganate through another, pulverized coal or gas through a third and combustion of the formed conical or diverging flame supported by the fuel-oil atomizer 67. In this instance, each component being introduced at predetermined static pressure or velocity, temperature, and state of aggregation, the potassium permanganate decomposes the hydrogen peroxide, which supplies oxygen for the combustion of the fuels, while the remaining water, in the form of steam, dilutes the gaseous products and prevents creation of a heat level exceeding the capacity of the furnace material employed. Other suitable combinations of substances, and appropriate static pressures or velocities, temperatures and states of aggregation therefor, will be apparent to those skilled in the art.

A modified form of the invention, likewise adapted to feed a diversity of substances, at different static pressures or velocities, temperatures, and in different states of aggregation, simulta-

neously to the furnace through the annuli of a diffuser that is adjustable fore and aft in a register, whereby converging or diverging flame patterns of desired shape and intensity can be created, is shown in Figs. 3 and 4.

A plurality of concentric conduits form a trunk 83, said trunk being carried slidably for adjustment fore and aft in the exterior wall of a furnace by suitable means (not shown). Each conduit of said trunk feeds into one of a plurality of nested manifolds, which forms a multiple manifold 85. A multiplicity of conduits are fed from said manifold, with a plurality of said conduits arranged concentrically to form a branch 87, said branch including conduits fed from each of said nested manifolds, and branches 89, 91, 93, 95 and so forth to any desired number of branches formed similarly. Thus, communication of combustion constituents is effected from the trunk 83, comprising a plurality of concentric tubes, through nested manifolds that form multiple manifold 85, and then through multiple branches 89, 91, 93, 95 and so forth, each branch comprising a plurality of concentric tubes, each of the individual tubes in a branch being in communication with the corresponding tube in said trunk.

Each of said branches terminates in a frusto-conical mouth 97 including a plurality of frusto-conical annuli 99, upstanding lips 101 thereon, supporting-bars or spreaders 103 securing said mouths in spaced relation, and converging annuli 105 secured to said spreaders and lips to define, in combination with the conduits of each of said branches, a plurality of individual passageways, the construction of each branch being substantially similar to that shown in Fig. 1.

Each branch is further provided with a mounting frame 107 encircling the outermost annulus, each said frame being secured to adjacent frames to maintain said frames in desired spaced relation. Preferably, said branches are clustered to define a frusto-conical figure, as shown in Figs. 3 and 4.

Operation of the diffuser shown in Figs. 3 and 4 is substantially the same as the operation of the preferred embodiment hereinabove described, except that higher flame concentration and more precise flame pattern is achieved.

Various modifications and changes can be made in the subject device without departing from the scope of the invention.

The invention described herein may be manufactured and used by or for the Government of the United States of America for governmental purposes without the payment of any royalties thereon or therefor.

I claim:

1. A diffuser comprising a first conduit having an outwardly flared mouth, a first frusto-conical annulus mounted on and diverging from said mouth, a second conduit having an outwardly flared mouth and an upstanding lip nesting said first conduit and said first annulus, a second frusto-conical annulus mounted on and converging from the peripheral edge of the lip of said second conduit, a third conduit having an outwardly flared mouth and an upstanding lip nesting said second conduit, and a third frusto-conical annulus mounted on and converging from the peripheral edge of the lip of said third conduit nesting said second annulus.

2. A diffuser comprising a plurality of nested conduits each having an outwardly flared mouth, a first frusto-conical annulus mounted on and diverging from the mouth of the innermost of

said conduits, and a plurality of frusto-conical annuli mounted on and converging from the mouths of the other of said conduits, the minor diameters of said last-mentioned annuli being greater than the major diameter of said first annulus, the peripheral edges of said plurality of annuli defining a diverging frustum.

3. A diffuser comprising a plurality of nested conduits each having an outwardly flared mouth and an upstanding lip, a first frusto-conical annulus mounted on and diverging from the mouth of the innermost of said conduits, a first plurality of frusto-conical annuli mounted on and converging from the peripheral edges of said lips, a second plurality of frusto-conical annuli subdividing the passages defined by said first plurality of annuli, the minor diameters of said first and second plurality of annuli being greater than the major diameter of said first annulus, the peripheral edges of said first and second plurality of annuli defining a diverging frustum.

4. A diffuser comprising a plurality of diffuser branches, each branch comprising a plurality of nested conduits each having an outwardly flared mouth and an upstanding lip, a first frusto-conical annulus mounted on and diverging from the mouth of the innermost of said conduits, a

5

plurality of frusto-conical annuli mounted on and converging from the peripheral edges of said lips, the minor diameters of said last-mentioned annuli being greater than the major diameter of said first annulus, the peripheral edges of said plurality of annuli defining a diverging frustum, said branches being arranged to define a diverging shallow cone.
